Barracuda Triton Swim Goggle, announced unknown, [online], [site visited Jul. 14, 2018]. Available from Internet, <URL: <https://barracuda101.com/collections/goggles/products/barracuda-swim-goggle-triton-wire-frame-technology-for-adults-men-women-33925?var>> (Year: 2018).*

Primary Examiner — Michelle E. Wilson*Assistant Examiner* — Sanjeev Paul(57) **CLAIM**

The ornamental design for a swimming goggle, as shown and described.

DESCRIPTION

FIG. 1 is a perspective view of a swimming goggle showing my new design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top plan view thereof; and,

FIG. 7 is a bottom plan view thereof.

The broken lines in the FIG. 3 illustrate portions of the swimming goggle that form no part of the claimed design.
